DIAPHRAGM FOR SOUND-BOXES.

1,316,703.

Specification of Letters Patent. Patented Sept. 23, 1919.

Application filed March 28, 1915, Serial No. 17,100. Renewed April 23, 1917. Serial No. 164,049.

To all whom it may concern:

Be it known that I, JAMES H. ELLIS, a citizen of the United States, and resident of Milwaukee, in the county of Milwaukee and State of Wisconsin, have invented new and useful Improvements in Diaphragms for Sound-Boxes, of which the following is a description, reference being had to the accompanying drawings, which are a part of this specification.

This invention has for its object to provide in the sound boxes of sound recording or reproducing instruments, a diaphragm which will have its stylus connection so arranged that in the operation of the instrument the diaphragm is bent or warped instead of being convexed first on one side and then on the other. Diaphragm connections have heretofore been so arranged as to give the center of the diaphragm a maximum movement along the axis of the sound box, but the present invention contemplates a construction whereby a comparatively slight movement of the center of the diaphragm is produced with a greater movement on either side thereof, the center constituting in effect a fulcrum about which the parts having the maximum movement bend in opposite directions to produce a wave-like formation. This is effected by the use of an angular anchor post with its link connection with the stylus lever offset with relation to the stem or shank portion thereof which connects with the diaphragm so that the line of direction of force applied to the diaphragm anchor post is approximately parallel with and slightly distant from the stem portion of the anchor post. Thus the line of direction of the force does not include the point of connection of the connecting post with the diaphragm and tends to exert a lateral stress upon the connecting post as if to push or pull said connecting post over against the diaphragm, but the connection of the post with the diaphragm not permitting this, the diaphragm becomes warped or bent in opposite directions on either side of the connecting post somewhat in the same manner as the stretched string of a musical instrument vibrates in reverse curves on either side of its normal position of rest.

The invention also has for its object to provide a diaphragm of sheet ivory as being a most suitable material to be influenced

by or to produce sound wave vibrations, a further object being to provide a diaphragm with notched edges to assist in maintaining its spaced relation to the walls of the sound box while clamping it in place, such notches serving to permit the flexible gaskets to be pressed into them to constitute spacing lugs or pads for this purpose.

With the above and other objects in view the invention consists in the sound producing or recording device as herein claimed and all equivalents.

Referring to the accompanying drawings in which like characters of reference indicate the same parts in the different views:

Fig. 1 is a plan view of a device constructed in accordance with this invention; Fig. 2 is a sectional view thereof applied to a sound box;

Fig. 3 is a detail view thereof showing the anchor post;

Fig. 4 is a similar view of a modified form of the invention as adapted for disk record machines; and,

Fig. 5 is a plan view of the diaphragm with this modified form of connection.

Figs. 6 and 7 are detail views of further modifications.

In these drawings 10 indicates a diaphragm which is preferably, though not essentially, of sheet ivory, and is of a disk-like shape with notches 11 formed in its edge at intervals in order that when the diaphragm is clamped in place in the sound box 12 between the gaskets 13 of rubber or other flexible material, such gaskets may bulge into the notches or recesses in the edge of the diaphragm and serve thereby to prevent displacement of the diaphragm which might permit its edge to come in contact with the wall of the sound box, for it is well known such contact results in a very disagreeable sound being produced by the diaphragm.

An angular anchor post is secured to the diaphragm, preferably to one side of the center of the diaphragm, with its eye for the connecting link of the stylus lever in the axis of the sound box or the line through the center of the diaphragm and perpendicular thereto. This anchor post may be, and preferably does consist of a strip 14 of the material of which the diaphragm is made cut to a tapering form and inserted through a slot in the diaphragm of proper dimen-

2

sions to make a snug fit therewith, the larger end of the strip binding against the ends of the slot as a wedge. The larger end of the strip 14 which does not pass through the slot in the diaphragm is covered with a celluloid cement 15, or other liquid or plastic covering that will harden on drying, and at the other side of the diaphragm the strip 14 has one or more indentations 16 formed therein and the cement is filled therein and along the meeting edges between the strip 14 and the diaphragm to form a fillet therefor, and all serving to rigidly secure the strip 14 to the diaphragm. Although the strip 14 is comparatively broad and flat it is for convenience referred to as the shank or stem portion of the anchor post of which it forms a part and near its outer edge it has an arm 17 of similar material mounted in it in the same manner that it is mounted in the diaphragm, and said arm lies in a plane perpendicular to the diaphragm and including the axis thereof. The strip or plate 14 forming the stem of the anchor post is positioned a short distance to one side of the center of the diaphragm and the arm 17 is provided with an opening in the axis of the diaphragm or the axis of the sound box which is considered to be the line through the center of the diaphragm and perpendicular therewith. Through this hole is connected a connecting link 18 of the usual stylus lever 19.

In operation the movements of the stylus lever incident to the irregularities in the path of travel of the stylus carried thereby are transmitted to the diaphragm, but instead of the connection between the stylus lever and the diaphragm being direct it is made through the angular anchor post, and the connection with such anchor post being out of alignment with the stem portion thereof the tendency is to bend the anchor post over against the diaphragm and as this is resisted by the firm connection between the anchor post and the diaphragm a distortion of the diaphragm is produced to give it a warped or wave-like shape with the portion on one side of the anchor post convexed in one direction and the portion on the other side convexed in the opposite direction. A reversal in the direction of the force applied to the diaphragm through the operation of the stylus lever will of course reverse the direction of the bending of the diaphragm so that the diaphragm vibrates with a wave motion with one side above the normal position and the other side below the normal position in one instant and these positions reversed immediately following. This diaphragm construction produces sounds free from mechanical blast and remarkably true in quality to the original tones, even with the extremely high and extremely low notes.

66 While the anchor post may be centrally

positioned on the diaphragm, it is preferred to position it to one side of the center, as shown, with the stylus connection in the line of the axis of the diaphragm as it is found that the results are somewhat better in this 70 location of the parts.

The principles of this invention are applicable to diaphragms for sound boxes of disk record machines by riveting the end of the stylus arm 20 to the anchor post arm 17 75 in the manner shown in Figs. 4 and 5. With this construction the same movements of the diaphragm are produced with the same beneficial results and advantages.

While the diaphragm and the anchor post 80 may be of other suitable materials it is found that ivory is superior for the purpose.

The anchor post is itself flexible, though rigidly connected with the flexible diaphragm, and the manner in which it is connected assures a sufficiency of responsive movement of the diaphragm to give volume as well as quality and accuracy in the reproduced sound.

The angular shape of the anchor post is 90 not alone responsible for the warping effect of the diaphragm, for this effect would be lost with an angular anchor post if the line of direction of the force applied thereto should be such as to intercept the point of 95 connection of the anchor post with the diaphragm. The warping effects might also be produced by an anchor post which, though not angular, is in an oblique position with respect to the diaphragm, as shown in Fig. 100 6, or has the line of force oblique with respect thereto, as shown in Fig. 7, so that in either case such line of force does not pass through the diaphragm at the point of connection between the anchor post and the 105 diaphragm.

What I claim as new and desire to secure by Letters Patent is:

1. The combination of a diaphragm, a thin sheet of flexible material, a stylus operated member, and an anchor post connected with the stylus operated member and secured to and solely supported by the thin sheet of flexible material at one side of the line of movement of the connection between 110 the stylus operated member and the anchor post.

2. The combination of a diaphragm disk of thin flexible material, a stylus operated means having a direction of movement approximately in the axis of the disk, and an anchor post secured to and solely supported by the disk at a distance from the center of the disk and having connection with the 120 said means in the line of the axis of the 125 disk.

3. The combination of a diaphragm disk of thin flexible material, an anchor post secured to and solely supported by the disk at a distance from the center of the disk and 130

having a laterally projecting arm reaching to the axis of the disk, and a stylus operated means connected with said arm at a point near the axis of the disk.

5 4. The combination of a diaphragm disk
of thin flexible material, an angular anchor
post comprising a stem portion secured to
and solely supported by the disk and ap-
proximately perpendicular thereto, and an
10 arm portion extending laterally from the
stem portion, and a stylus operated means
connected with the arm portion.

5. The combination of a diaphragm disk of thin flexible material, an anchor post comprising a stem portion connected with and solely supported by the disk at a distance from the center of the disk and having a

laterally extending arm reaching to the axis of the disk, and a stylus operated means connected with the arm at a point near the axis of the disk. 20

6. The combination of a diaphragm disk of thin flexible material having a slot therethrough, a tapering strip of flexible material fitting in the slot and secured to the 25 disk, a tapering arm fitting in an opening of said strip and projecting laterally therefrom, and a stylus operated means connected with the arm at a distance from the strip.

In testimony whereof I affix my signature 30
in presence of a witness.

JAMES H. ELLIS.
